UNITED STATES PATENT OFFICE.

GEORGE W. PIPE, OF ST. PAUL, MINNESOTA.

RAILROAD WHEEL CLAMP.

1,402,793.

Specification of Letters Patent. Patented Jan. 10, 1922.

Application filed February 17, 1921. Serial No. 445,717.

To all whom it may concern:

Be it known that I, GEORGE W. PIPE, a citizen of the United States, residing at St. Paul, in the county of Ramsey and State 5 of Minnesota, have invented a new and useful Railroad Wheel Clamp, of which the following is a specification.

My invention relates to devices for replacing worn out bushings or so called "brasses" 10 in journal bearings of railroad car axles, and the object is to provide a simple and efficient device of said kind.

In the accompanying drawing;

Fig. 1 is a vertical elevation of my 15 device, the adjacent parts of a car truck and a portion of a railroad track the latter two being shown partly in section.

Fig. 2 is a sectional view on line 2--2 of Fig. 1.

20 Referring to the drawing by reference numerals 3 represents a rail, 4 a tie of a railway track, 5 a car wheel with rail flange 6, tread flange 7, web 8 and hub 9. The axle 10 fitted in the wheel hub and projecting 25 through same has a flange 11 at the outer end of its bearing portion 12.

In the usual railroad car truck construction a journal box 13 has a semi-cylindrical seat 14 for a correspondingly shaped flanged 30 semi-cylindrical bushing 15 the inner surface of which contacts with the journal 12 of the axle 11.

The journal box is of the usual hollow construction extending below the axle and outward 35 beyond the end of the axle where it has an opening 16, permitting oily rags or waste 17 to be placed in the box around the axle and thus lubricating the latter.

The main part of my device is a clamp 18

preferably made of high grade steel and 40 large enough to straddle the tread 19 of the rail and rim 7 of the wheel. Preferably the clamp may have a set screw 20 in the top end of it. A common jack screw 21 with handle 21^x, placed on a plank 22, which may extend 45 across 2 or more ties, is placed directly back of the clamp directly under the journal box 13 in position to raise the latter. A rearwardly projecting lug 23 on the clamp may be used as a buffer against the jack to keep 50 the clamp from slipping away from the rail and the wheel flange. Lug 23 has vertically projecting side arms 23^x adapted to straddle handle 21^x of the jack, as shown in Fig. 1.

In the application and operation of my 55 device when the jack screw is applied the head of the jack screw gradually raises the journal box approximately to dotted position in Fig. 1, the wheel remaining clamped to the track and the journal box bearing 60 being raised above the axle leaves the bushing 15 free and accessible so that it can be removed and replaced with a new bushing. The device thus overcomes the well known trouble that the wheel will raise with the 65 journal box.

What I claim is:

In a device of the kind described, a screw clamp straddling a portion of the car wheel and the adjacent portion of the track rail, a 70 lifting device mounted on the ties near the said rail for lifting the journal box, said clamp having an outwardly projecting arm with spaced vertical lugs arranged to engage the lifting device and prevent both slipping 75 and turning movement of the clamp.

In testimony whereof I affix my signature.
GEORGE W. PIPE.
